CLAIM

The ornamental design for a pack sleeve with pocket, substantially as shown and described.

DESCRIPTION

FIG. 1 is a front, right side and top perspective view showing a first embodiment of a pack sleeve with pocket in a closed position according to our new design, the other side being a mirror image thereof.

FIG. 2 is a front, right side and bottom perspective view thereof, the other side being a mirror image thereof.

FIG. 3 is a front elevational view thereof.

FIG. 4 is a left side elevational view thereof.

FIG. 5 is a right side elevational view thereof.

FIG. 6 is a top plan view thereof.

FIG. 7 is a bottom plan view thereof.

FIG. 8 is a back elevational view thereof.

FIG. 9 is a front, right side and top perspective view thereof in an open position thereof, the other side being a mirror image thereof.

FIG. 10 is a front, right side and top perspective view showing a second embodiment of a pack sleeve with pocket in a closed position according to our new design, the other side being a mirror image thereof.

FIG. 11 is a front, right side and bottom perspective view thereof, the other side being a mirror image thereof.

FIG. 12 is a front elevational view thereof.

FIG. 13 is a left side elevational view thereof.

FIG. 14 is a right side elevational view thereof.

FIG. 15 is a top plan view thereof.

FIG. 16 is a bottom plan view thereof.

FIG. 17 is a back elevational view thereof; and,

FIG. 18 is a front, right side and top perspective view thereof in an open position thereof, the other side being a mirror image thereof.

The broken lines are shown for illustrative purposes only and form no part of the claimed design.
